UNITED STATES PATENT OFFICE.

JOSEPH McKIERNAN, OF NEW YORK, N. Y., ASSIGNOR TO THE BIGELOW CARPET COMPANY, A CORPORATION OF MASSACHUSETTS.

DESIGN FOR A RUG.

41,111.

Specification for Design.

Patented Jan. 17, 1911.

Application filed October 26, 1910. Serial No. 589,268. Term of patent 3½ years.

To all whom it may concern:

Be it known that I, JOSEPH McKIERNAN, a citizen of the United States, residing at New York city, in the county of New York and State of New York, have invented a new, original, and ornamental Design for a Rug, of which the following is a specification, reference being had to the accompanying drawing, forming part thereof.

The drawing illustrates one quarter of a rug showing my new design, the remaining three quarters being duplicates thereof.

I claim:

The ornamental design for a rug, as shown.

JOSEPH McKIERNAN.
